CLOSURE FOR A FOOD MOLD OR THE LIKE

James B. Swett, Barrington, and Harold P. Ashton,
Providence, R.I., assignors to Dart Industries, Inc., Los
Angeles, Calif., a corporation of Delaware

Filed Aug. 13, 1969, Ser. No. 18,663

Term of patent 14 years

Int. Cl. D7—99

U.S. Cl. D44—1

FIG. 1

FIG. 2

FIG. 3

FIG. 1 is a top perspective view of a closure for a food mold or the like showing our new design;

FIG. 2 is a bottom perspective view thereof; and

FIG. 3 is a cross-sectional view along line 3—3 of FIG. 1.

We claim:

The ornamental design for a closure for a food mold or the like, substantially as shown.
